PETE SWISHER, OF VERSAILLES, OHIO.

Letters Patent No. 60,960, dated January 1, 1867.

IMPROVEMENT IN BURGLAR ALARM GUNS.

The Schedule referred to in these Letters Patent and making part of the same.

TO ALL WHOM IT MAY CONCERN:

Be it known that I, PETE SWISHER, of Versailles, in the county of Darke, and State of Ohio, have invented a new and improved Burglar Alarm Gun; and I do hereby declare that the following is a full, clear, and exact description thereof, which will enable others skilled in the art to make and use the same, reference being had to the accompanying drawings, forming part of this specification, in which—

Figure 1 is a side view of my improved burglar alarm gun, partly in section.

Figure 2 is a top view of the same.

Similar letters of reference indicate like parts.

This invention relates to an improved compound gun, having several barrels, so connected and arranged as to be fired simultaneously, and aiming in different directions, as a defence against burglars. It is designed to attach it to a door or window through which a burglar may enter, the opening of which door or window will cause the trigger of the gun to be pulled, and discharge it, when the explosion will alarm the household and probably shoot the burglar, as the barrels may be so placed as to bring him in range at several points of entrance.

In the drawing, fig. 1, is shown a gun or pistol, with three barrels, 1, 2, 3. The upper barrel, No. 1, is permanently fixed upon, or forms a continuation of, an iron handle or stock, A, with which it may be fastened by a clamp, or in any convenient manner, to the door frame or other object where the gun may be required, and in which is the lock for operating a hammer, B. The lock may be of any ordinary construction. *a* is a trigger, to spring the hammer, by means of a wire attached to the door or window to be opened by the burglar; *b* is the cap cone. A round metal breech-pin, C, is screwed firmly at right angles to the under side of the breech of the barrel No. 1, in the middle of which pin is a small hole, *c*, running longitudinally, and communicating with the vent of the upper barrel, No. 1. The two barrels, Nos. 2 and 3, are fitted upon the breech-pin C, as a pivot on which they turn around, to be placed at any point, and range in different directions, as desired for shooting, and are held in place upon the pin by a screw-nut, *d*, on the lower end of the pin. The bores *m m* of the barrels 2 and 3 extend back to the pivot breech-pin C, and communicate with annular grooves, *e e*, on the periphery of the pin, in line with them; and the grooves *e e* communicate with the central longitudinal hole *c* of the breech-pin by small transverse holes, *n n*, all of which grooves and holes in the breech-pin C are priming or touch-holes, to be filled with powder when the barrels are loaded.

The operation, or manner of firing all the barrels at once, in whatever position the two lower ones, 2 and 3, may be placed on the breech-pin C, is manifest, as the bores *m m* are always in communication with the annular grooves *e e* when the barrels are revolved upon it, and the holes *n n* leading from the grooves connect with the central hole *c*, which communicates with the vent of the upper barrel, No. 1. Thus, the train of powder which fills them is fired, and discharges all the barrels simultaneously, when the cap is exploded by the hammer B. On the side of the stock A is fastened a small powder pan, *h*, which communicates with the vent of the upper barrel. It may be filled with powder when the alarm gun is set, and a match and candle so connected with it as to be lighted when the gun is fired.

Having described my invention, I claim as new, and desire to secure by Letters Patent—

1. In the construction of a burglar alarm gun, the combination of the fixed barrel, No. 1, and the revolving barrels 2 and 3, with the breech-pin C, for firing simultaneously in different directions, substantially as and for the purposes herein described.
2. I claim the breech-pin C, having the central longitudinal hole *c*, the transverse hole *n*, and the annular grooves *e*, communicating with the vent of the upper barrel No. 1, and the bores of the revolving barrels Nos. 2 and 3, all arranged and operated substantially as and for the purposes herein described.
3. I claim also the outside powder pan *h*, for lighting a candle or lamp when the gun is fired, in the manner herein specified.

P. SWISHER.
